United States Patent Office.

JOHN KOCH, OF BROOKLINE, MASSACHUSETTS.

Letters Patent No. 72,507, dated December 24, 1867.

IMPROVEMENT IN STAIRS.

The Schedule referred to in these Letters Patent and making part of the same.

TO ALL PERSONS TO WHOM THESE PRESENTS MAY COME:

Be it known that I, JOHN KOCH, of Brookline, in the county of Norfolk, and State of Massachusetts, have invented a new and useful Improvement in Stair-Steps; and I do hereby declare the same to be fully described in the following specification, and represented in the accompanying drawings, of which—

Figure 1 is a top view,

Figure 2 a front edge view,

Figure 3 a longitudinal section, and

Figure 4 a transverse section of a stair-step, as provided with my improvement, which consists in the combination of a plate of cork with the tread or floor of the step, the plate of cork being inserted within such plate or floor.

The object of the plate of cork is to form not only an elastic surface for the foot of a person to step on, but a surface which will prevent the foot from slipping on the stair. By arranging the cork within and so as to fill a corresponding recess made in the step, the ends and rear edge of the cork plate will be protected by the wood from injury.

In the drawings, A denotes a stair-step, or the top board or floor thereof. B is the plate of cork inserted in a recess, C, made in the step or part A.

I claim the combination and arrangement of the plate of cork with the stair-step, the whole being as and for the purpose hereinbefore specified.

JOHN KOCH.
